W. F. BEATTY,
ICE CREAM CABINET,
APPLICATION FILED MAR. 22, 1920.

1,370,270.

Patented Mar. 1, 1921.

UNITED STATES PATENT OFFICE.

WILLIAM FRANKLIN BEATTY, OF CINCINNATI, OHIO.

ICE-CREAM CABINET.

1,370,270.

Specification of Letters Patent.

Patented Mar. 1, 1921.

Application filed March 22, 1920. Serial No. 367,766.

To all whom it may concern:

Be it known that I, WILLIAM F. BEATTY, a citizen of the United States, and a resident of Cincinnati, in the county of Hamilton and State of Ohio, have invented a certain new and useful Improvement in Ice-Cream Cabinets, of which the following is a specification.

This invention relates to dispensing-cabinets for use in the sale or serving of ice-cream or the like, more particularly at soda-fountains, and its object is to provide a device for facilitating the lifting or raising of the ice-cream can or receptacle from an offsetted or shouldered jacket-structure peculiar to me in soda-fountain apparatus, the details being hereinafter fully referred to in connection with the accompanying sheet of drawings, in which—

Figure 1 is a cross-section (from front to rear) of an ice-cream cabinet embodying my invention fully; Fig. 2, a detail perspective view of the can-lifter itself; Fig. 3, an elevation of the offsetted or shouldered jacket-structure with my can-lifter in place; Fig. 4, a sectional elevation of the said offsetted or shouldered jacket-structure, with my can-lifter shown in normal position therein, but with a special form of spacing and take-up or compensating ring seated on the offsetted portion of the jacket-structure to allow for cans of smaller size or diameter than that of a sliding or approximately contact fit within the jacket, a can of said smaller size being shown in dotted-lines in using place in the said jacket; and Fig. 5, a detail plan of the side-swinging lid used by me to cover the orifice or opening in the cabinet top provided for access to the open ice-cream can beneath.

The cabinet is composed of upright walls 6, a bottom 7 and a top member or cover, the latter having a horizontal rear-portion 8 and a sloping fore-portion 9, and all the said walls and bottom being suitably insulated or lined as shown at 10.

This cabinet has an ice-chamber, within which is placed a metal jacket 11 arranged preferably at an inclination, as shown in Fig. 1, to correspond to the sloping fore-portion 9 of the cover. An inclined partition 12 is placed in the ice-chamber to take up part of the surplus space forward of the said jacket, to economize in the supply of ice and, also, to keep up such supply close to

the jacket for the desired refrigeration. This partition also renders the cleaning of the ice-chamber more convenient and thorough. The ice meltings are drawn off through the plugged discharge 13.

60

The metal jacket 11 has an offset or a shoulder 14 made therein near its upper or outer end, the latter forming an enlarged mouth 15, and with a ring or gasket 16 resting upon the edge or rim of the latter within an opening or orifice 17 made in the sloping fore-portion 9 of the cabinet cover.

A lid 18 is provided over the orifice 17 and is preferably hung by means of a bar or strap 19 that extends from a center pin or screw 20 to a pivot-pin 21 that projects from the forward edge of the horizontal rear-portion 8 of the cabinet cover, as best seen in Fig. 1. The outer end of the center-pin 20 forms a handle by which to manipulate the 75 lid 18 in a swinging or circular manner around the rear-pin 21 so as to afford easy access to the contents of the can or receptacle 22 that rests within the shouldered or offsetted jacket 11, the outer mouth-end of 80 the can 22, for an approximate distance of six inches, more or less as desired, extending beyond the offset or shoulder 14, such extended mouth-portion of the can being one of the important features of the invention 85 herein and intended for the convenient and free grasping-access thereto of the hands of the person handling the can to and from place within the jacket 11. The can 22 itself is ordinarily a lidless one and its outer 90 edge in use is preferably somewhat but not greatly below the gasket or ring 16 in the orifice 17 of the cabinet cover so as to allow the hands easy holding-access to the rim for inserting or removing the can, when filled or 95 empty, as the case may be.

For better and still further handling of the can 22, to and from the jacket 11, I provide a pull-rod 23, best shown in detail in Fig. 2, and one of the important features of 100 the invention herein. This pull-rod has an angular foot-piece 24 and a manipulating-handle 25. It is preferably made of a strip of flat metal and the foot-piece is several inches in length for extending under the 105 lower edge of the can, as best shown in Fig. 1, to withdraw said can from the jacket, or for starting the withdrawal thereof until its upper edge or mouth-end extends above the fore-orifice 17 in the cabinet cover, where it 110

may be easily taken hold of and further removed altogether.

- 5 The outward or longitudinal movement of the pull-rod 23 is limited to the distance its foot-piece 24 may travel in a vertical slot 26 made in the jacket, such slot being best shown in Fig. 3, but also well shown in Figs. 1 and 4, the main part of the pull-rod passing upwardly through a guide-clip 27 on the 10 jacket and thence through a slot or opening 28 made in the offset or shoulder 14 of the jacket, up to a point just below the gasket or ring 16 where its handle 25 may be readily located and grasped.
- 15 The jacket 11 is provided with a number of small openings or perforations 29 for circulation of the cooling medium from the ice-chamber into the narrow annulus or space 30 surrounding the cream can within 20 the jacket, such cooling medium not being liable to overflow into the mouth of said open cream can when the cabinet is in use and thoroughly preserving the cream in a prime frozen but pliable state.
- 25 As it may happen that some of the ice-cream cans are considerably smaller in size or diameter than the average or standard ones in general use, I provide a removable reducer-ring 31 that has an extension flange 30 or downturned rim 32 (Fig. 4) whereby it may be safely seated or rested on the offset 14 and thus fill the space or compensate for the said lesser diameter of can to centralize the latter within the jacket and hold it

firm for the desired dispensing or dishing 35 of the cream.

An orifice 33 is provided in the horizontal rear-portion 8 of the cabinet top or cover, and a hinged lid 34 used to close same, whereby access to the ice-chamber is readily 40 had for filling same and replenishing it with ice from time to time independent of and without interfering with the cream-dispensing opening in the sloping fore-portion 9 of the said cover. 45

I claim:—

1. In an ice-cream cabinet having upright walls and a suitable bottom, an ice-chamber, a jacket in said ice-chamber having an offset or shoulder between its closed bottom and open top whereby the latter is enlarged in diameter, a cream-can in the offsetted jacket with its upper mouth-end extending beyond the offset in said jacket but below the cream-dispensing orifice of said top, and a vertical 50 pull-rod having a foot-piece at its lower end and a handle at its upper end, the said foot-piece being adapted for engagement with the bottom of the cream-can for facilitating the withdrawal of the latter from place in 60 the jacket.

2. An ice-cream can jacket having an enlarged or outwardly-offsetted upper mouth-end and a reducer-ring or spacer adapted to rest on the upper offset in the jacket for the 65 provision of cans of lesser diameter than standard or average size ones.

WILLIAM FRANKLIN BEATTY.
